CLAIM

The ornamental design for a wall lamp, as shown and described.

DESCRIPTION

1. Wall lamp

Fig. 1.1 is a top perspective view of a wall lamp, showing my new design; fig. 1.2 is a bottom perspective view thereof; fig. 1.3 is a rear view thereof; fig. 1.4 is a front view thereof; fig. 1.5 is a right view thereof; fig. 1.6 is a left view thereof; fig. 1.7 is a top view thereof; fig. 1.8 is a bottom view thereof; fig. 1.9 shows an alternate position (closed lamp); fig. 1.10 shows an alternate position (open lamp).

The broken lines shown in the drawings are for the purpose of illustrating portions of the wall lamp that form no part of the claimed design.
